EDMUND FOSS, OF SEATTLE, WASHINGTON, ASSIGNOR OF ONE-THIRD TO MAX VOLLMER AND ONE-THIRD TO FRANK F. HOPKINS, BOTH OF SEATTLE, WASHINGTON

DOOR FOR FREIGHT CARS

Application filed January 22, 1927. Serial No. 162,823.

In operating freight cars in the winter time, and particularly those which carry live stock, it has been found that the sliding door of ordinary construction to be found therein, often becomes bound to the car by the freezing of water or other liquids which percolate between the floor or body of the car and the lower edge of the door, with the result that it becomes necessary, even in new cars, to pry the door open, and, in addition to the extra work involved and time consumed, injury is sometimes caused to the door or car.

To do away with this objectionable feature and in the interests of facility of operation and economy, I provide, as the objects of my invention:

First, a car door having not only a sliding longitudinal movement relative to the car, but a lateral movement as well, and whereby the door may be readily made free of any such obstruction; second, means for achieving this result which can be applied to a car door of usual type, and thereby convert it into my improved door at comparatively small expense; and, third, a freight car door so exceedingly simple in construction which, notwithstanding its enhanced utility, may be produced at a low cost.

Other objects may appear as the description of the invention progresses.

In the accompanying drawing—

Figure 1 is a side elevation of the door mounted on a freight car and in locked position;

Fig. 2, a horizontal section drawn on the line 2—2, of Fig. 1;

Fig. 3, an enlarged detail view showing a portion of the door broken away, one of the jambs of the door on which certain of the door fixtures are mounted, and a side of the car broken away, all being in cross section; a sill of the car broken away, a bracket secured to the jamb, and, in cross section, a vertically extending rod, pivoted therein, carrying a locking-arm for the door;

Fig. 4, an enlarged detail view of the same portions of the door and car, showing said rod carrying a locking-hasp, and a handle, locking and sealing mechanism connected

with the door for securing the same in closed position;

Fig. 5, an enlarged detail view of similar portions of the door and car located on the side oppositely of the first-named portions, illustrating a locking-hook projecting from the adjacent lower corner of the door, and a funnel-like recess in which its free end is disposed, said end being located so as to permit lateral movement of the hook in the recess; and,

Fig. 6, a vertical section through the center of said recess, indicating in cross section the free end of the hook, as located therein when in locked position.

Referring more particularly to the drawing, 1 designates the side of a freight car of usual construction, 2 a sill disposed thereon, 3 the door jambs and 3' the lintel. The jambs extend outwardly from the side of the door, and top and bottom portions are provided, which, in connection with the jambs, form a frame around the door opening therein, having its members disposed in the same plane, and on which the door is placed. The body of the door 4, the roller hangers, generally designated as 5 and the rail and supporting elements therefor, denoted generally as 6, which afford a longitudinal sliding movement for the door, and the metallic band 7, protecting the upper edge of the door, are of usual construction and constitute no part of this invention.

A pair of brackets 10, secured to one of said jambs, pivotally support a vertically extending rod 11, having adjacent each end a locking-arm 12 to prevent lateral movement of the door, the upper one of which operates against a metallic plate 13, secured to the door, and the lower one against a metallic band 14, fastened to and projecting from the lower edge of the door.

A locking-hasp 15, extending from said rod, is provided with a transverse slot 16, having centrally thereof a circular opening 17 and an upstanding apertured projection 18, the purpose of which opening and projection will presently appear. A plate 19, affording a metallic seat for the hasp when the same is in closed position, is bolted to

the door, said bolts, as it may be noted in Fig. 4, also serving to secure at the rear of the door and opposite said plate, a housing denoted as 20. Another housing 21 extends through the door, and is disposed between the plate 19 and the first-named housing, the said plate and housings affording means whereby the handle 22 may be mounted and its cylindrical shank portion 23 enclosed, as indicated in Fig. 4. Said shank is provided at its rear end with a coiled spring 24 and retainer 25, and at its forward end with an enlarged shoulder-forming portion 26, which is circular in cross section and of a diameter conformable to and rotatable within the circular opening in the hasp. The plate 19 is apertured to rotatably receive that portion of the shank only which is of smaller diameter and denoted as 23, thus limiting the longitudinal movement of the shank within the housings and said shoulder to an exterior contact with said plate. A seal 27 is secured in place through the openings in the handle and the upstanding projection 18 on the hasp.

This door, through the roller hangers 5, is hung on the rail 6, and derives its sliding longitudinal movement solely from these instrumentalities, the locking means just described being designed to limit its movement both longitudinally and laterally from one side. When it is desired to thus lock the door at said side, the handle is disposed in a horizontal position, as indicated by the dotted lines in Fig. 4, and the rod 11 turned so as to bring said hasp thereover and in contact with the plate 19, the locking-arms 12 then assuming the positions against the door shown in Fig. 1. The shoulder 26, rotatable as it is within the opening 17 in the hasp, permits the handle to assume a vertical position, at the same time preventing any longitudinal movement of the door on account of the slot 16, and the spring 24, exerting pressure on the handle, keeps it in said position. The door, hung as it is, is subject also to a lateral movement, and the means just referred to are obviously adapted, when in closed position, to prevent any such movement at the side of the door on which they operate.

When the door is thus closed, and to avoid any such lateral movement on the other side of the door, the band 14 carries an integral locking-hook 30 having its free terminal 31 disposed in a funnel-like recess 32. Said recess consists of a metallic housing, of the form illustrated, secured within the adjacent door jamb. A bore-like opening 33, communicating with the inner end of said recess and having an outlet at the other side of the jamb, permits the recess to be easily cleaned of snow or any extraneous matter which might become lodged therein. It is contemplated that a single locking-hook, as described, will be ample sufficient, in cooperation with the other

locking means, to hold the door against lateral movement when in closed position. While in the present and preferred embodiment of the invention the hook is shown as being integral with the band 14, it may be mounted on the door as a separate part, as illustrated at 34, Fig. 1, and if deemed desirable to provide the door with additional and similar locking means on said side, a funnel-like recess of the same construction described may be provided in said jamb for the locking-hook connected with the member 34, thus giving the door a plurality of locking connections therat.

In operating the door, when it is disposed as shown in Fig. 1, a reversal of the cycle of operation heretofore described will release said hasp and arms, and upon the door being moved slightly in a longitudinal direction, the free end of the hook will leave the inner end of the recess and assume a position within that portion of the recess which is more flared, as indicated in Fig. 5. Said hook, now having a lateral play in the recess, will permit the door, in view of the manner in which it is hung, to be moved, through the handle, laterally of the car and thus be freed of any obstruction which might bind the lower edge of the door. The door may then, as is evident, be completely opened by moving the same longitudinally through the roller hangers and rail provided. When the door is moved to closed position it contacts with the front of the jamb in which the funnel-like recess is located and the hook takes its position therein, when the hasp and the arms may be turned in place and the door closed as before mentioned.

To those skilled in the art, it will be seen that this device may be made applicable to an ordinary freight car, as no special construction in the car is required, and but slight alterations are necessary for it to receive and retain the parts.

I claim:

1. In a freight car provided with a door thereon having top suspension means and a longitudinal and a lateral movement relative to the car, means for locking one side of the door against longitudinal and lateral movement, a locking-hook projecting from the other side of the door, and a recessed section in a jamb of the door adapted to house the free end of the hook and permit a lateral movement of the door when said means are released.

2. In a freight car door construction provided with top suspension means, means for locking the door on one side, comprising a locking-hook projecting from one side of the door, and a funnel-like recess operatively disposed for housing the hook, and whereby the door may be shifted laterally without releasing the hook from said recess.

3. In a freight car door construction pro-

vided with top suspension means, means for locking the door on one side, and means for locking the door on the other side, comprising a locking-hook and a keeper for the hook, 5 whereby, when the first-named locking means is released and the door is moved slightly in a longitudinal direction, the door may be shifted laterally without disengaging the locking-hook from the keeper.

10 EDMUND FOSS.
